WINDOW FRAME AND SASH

John B. Olson and John P. Bethke, Fort Atkinson, Wis., assignors to James Manufacturing Company, Fort Atkinson, Wis.

Application July 20, 1936, Serial No. 91,478

5 Claims. (Cl. 189—67)

Our invention relates particularly to barn and poultry house windows but is also suitable for factories, warehouses and other buildings.

The general object is to provide a frame and sash which are impervious to weather conditions, is practically air tight and locked against opening from the outside when closed, and is secure against accidental movement from any cause when open.

10 A further object is to provide a small primary opening without raising the lower part of the sash out of its sealed position, thus to provide some ventilation and still prevent ingress of rain, snow or sleet under any weather conditions, and 15 whereby in the other open positions, the sash will prevent ingress of rain, snow or sleet except in very severe wind conditions and a sash which will prevent a harmful draft by deflecting all of the incoming air upward.

20 An important object of our invention is to provide a ventilating window which cannot be moved or jarred loose from any position nor rattled by the action of the wind, and wherein any position it may be left in, is practically a 25 locked position.

A still further object is to provide a sash which may be raised and swung inward from the top without being raised above the top of the frame; thus a very low ceiling will not prevent a full 30 opening of the window.

With the foregoing and other objects in view our invention resides in features of construction, the parts and combinations thereof, as herein-after set forth and claimed and shown in the 35 accompanying drawings in which:

Fig. 1 is a front elevation of one form of our improved frame and sash.

Fig. 2 is a side sectional view of the device as 40 illustrated in Figure 1, taken on line 2—2 of Figure 1.

Fig. 3 is a fractional section of the device taken on line 3—3 of Figure 1.

Fig. 4 is a fractional section of the device taken on line 4—4 of Figure 6.

45 Fig. 5 is a sectional elevation of the device as shown in Figure 2 with the sash partly open and taken on line 5—5 of Figure 1.

Fig. 6 is a fractional front elevation sectioned on line 6—6 of Figure 2.

50 Fig. 7 is a sectional view taken on line 7—7 of Figure 1.

Fig. 8 is a reduced side elevation illustrating our improved window as designed for rooms having low head room, the window being shown 55 open.

Summary of improvement: where window frame is formed of Z-shaped frame bars, the sash is formed of bars similar to the frame bars, the side rails being positioned when the window is closed, one on the outside and one on the inside, and the sash is secured to the frame by novel means which act to tightly hold the sash members together.

As thus illustrated our improved window comprises a frame consisting of a sill 10, side jambs 11—11 and top header 13, forming a frame, each of the foregoing members being Z shaped in cross section, as illustrated, the corners of the bars 5 being preferably mitered and welded together to thus form a smooth rigid frame.

We provide a sash made from bars similar to the frame bars, comprising the bottom rail 14, top rail 15 and side rails 16—16. These four members are preferably miter joined and welded similar to the frame. The side members 11 and 16 are positioned, when the window is closed, as clearly illustrated in Figure 7. The top header 13 and top rail 15 are positioned when the window is closed, as illustrated in Figure 2, and the bottom sill 10 and the bottom rail 14 are positioned when the window is closed, as clearly illustrated in Figures 2 and 3.

Thus it will be seen that the two frames have 20 the same depth, whereby when the window is closed, there are two spaced and sealed contacts, one on the outside and one on the inside and that we provide novel means which act to tightly hold these contacting members together, as will 25 hereinafter appear.

As a matter of convenience we have illustrated our sash as having six glass panes. Clearly the sash and frame may be made to accommodate any number and any sized panes and while the 30 device as illustrated in Figure 1 is higher than its width, the usual window for the present purpose is somewhat greater in width than in height.

It will be noted by scrutinizing Figures 5 and 8 that our improved sash is opened inwardly by 35 swinging the top away from the frame and lifting the sash from the bottom. The desired relative openings above and below the sash are secured by the length and position of connecting links as will hereinafter appear. The incoming air at the top opening is directed upward thus forming a slight vacuum below the sash which tends to also direct the air upward, which enters below the sash, thus preventing harmful drafts near the floor.

We provide an angle bar 18 which is secured to and positioned on sill 10, as illustrated in Figure 3, and a similar angle bar 19 is positioned similarly on side jambs 11—11. Bars 19 terminate as at 20, a portion of the inwardly extending lip of the angle being bent outwardly as at 21, thus forming a closure to the end of the guide channel formed by member 19.

Referring now to Figures 5 and 6; we provide two links 25—25, each being pivotally se- 55

cured at their upper ends to members 11 as at 26, the washer 27 answering as a suitable spacer between the two members. The lower ends of links 25 are pivotally secured to side rails 16 5 as at 28, a washer 29 acting as a suitable spacer; thus when the sash is lifted, the upper end will swing away from the frame as illustrated in Figures 5 and 8.

We provide a drip cap 30 which is secured to 10 member 14 and loosely embraces the outer flange of member 10 when the window is closed, as illustrated in Figure 3. We also provide brackets 31 which are secured to the bottom of member 30, as illustrated in Figures 2, 3 and 5, 15 each having projections 32 which extend into the channel formed by member 10, thus to prevent the lower end of the sash from swinging inward and away from the frame.

We provide angle guides 33 which are secured 20 to members 18 and 19, the rear end being positioned whereby when the sash is lowered, lugs 32 will contact member 33 and force the sash outwardly into its sealed position, as illustrated in Figure 3.

25 We provide means for locking the upper end of the sash into position as follows:

Spaced arms 35-35 are suitably secured to top header 13, as illustrated, each having cut out notches 36 and 36^a on their under sides. Spaced 30 brackets 38-38 act as hinges for the upper ends of depending loops 37, as illustrated. A loop extension 39 is suitably positioned to enter notches 36 and 36^a when loop 37 is in the position shown in Figure 2, and to be disengaged when loop 37 35 is moved to the position shown by dotted lines in Figure 5. A spring latch 40 acts to lock loop 37 to the position shown in Figure 2. We provide a handle 41 whereby the operator may easily move the sash by grasping loop 37 with one 40 hand and handle 41 with the other.

It will be seen that when the window is closed and loop 37 is in the position shown in Figure 2, the sash will be held in its sealed position and if loop 37 is then moved to the position shown 45 by dotted lines in Figure 5, the top of the sash will be moved out of contact with the frame and that the sash may be further moved to a position where member 39 will engage notch 36 whereby some ventilation is provided but without lifting the bottom of the sash out of its 50 sealed position; thus clearly a heavy wind will not blow rain, snow or sleet into the building when the sash is in this position.

We provide stops 45 which are preferably positioned and shaped as clearly indicated in Figure 5; thus the sash may be moved so lugs 32 will rest on either pair of stops as indicated in Figure 5. The weight and position of the sash and action of links 25 will cooperate to hold the 60 sash securely in either of the positions provided.

Thus is will be seen that the applicants' frame and sash are light, strong, pleasing in appearance and especially adapted to the service for which they were devised. We have shown and described the preferred embodiment of our invention. Clearly many detail changes may be made without departing from the scope and meaning of the appended claims.

Having thus shown and described our invention, we claim:

1. A device of the class described, comprising a frame and a sash therefor, each formed by similarly shaped and positioned Z bar irons whereby adjacent flanges contact when the sash is closed, 75 the side members of said sash and frame being

spaced to thereby form closures for the length of the sash when the sash is closed, guide members attached to the sides of said frame and adapted to cooperate with the outer flanges thereof and extending a distance from the bottom of the frame 5 to thereby form guide channels, guide pins secured to the bottom of said sash which project into said guide channels, links positioned in said closures having their upper ends pivotally attached to said frame near the top thereof and 10 having their lower ends pivotally attached to said sash at a point above the top of said guide channels when the sash is closed whereby when the top of said sash swings open on said links said pins will act as guides for the lower end of the 15 sash, spaced stops in said guide channels adapted to engage said pins whereby said sash may rest thereon in selective positions.

2. A device of the class described, comprising a frame and a sash therefor, each formed by similarly shaped and positioned Z bar irons whereby adjacent flanges contact when the sash is closed, the side members of said sash and frame being spaced to thereby form closures for the length of the sash when the sash is closed, guide members 20 attached to the sides of said frame and adapted to cooperate with the outer flanges thereof and extending from the bottom to near the vertical center of the frame to thereby form guide channels, guide pins secured to the bottom of said sash which project into said guide channels, links positioned in said closures having their upper ends pivotally attached to said frame near the top thereof and having their lower ends pivotally attached to said sash at a point above the top of 25 said guide channels when the sash is closed whereby when the top of said sash swings open on said links said pins will act as guides for the lower end of the sash, spaced stops in the rear side of said guide channels adapted to engage 30 said pins whereby said sash may rest thereon in selective positions, means on said frame and sash whereby said sash may be manually locked into a slightly open position.

3. A device of the class described, comprising a frame and a sash therefor, each formed by similarly shaped and positioned Z bar irons whereby adjacent flanges contact when the sash is closed, the side members of said sash and frame being spaced to thereby form closures for the length of the sash when the sash is closed, guide members 50 attached to the sides of said frame and adapted to cooperate with the outer flanges thereof and extending from the bottom to near the vertical center of the frame to thereby form guide channels, guide pins secured to the bottom of said sash which project into said guide channels, links positioned in said closures having their upper ends pivotally attached to said frame near the top thereof and having their lower ends pivotally 55 attached to said sash at a point above the top of said guide channels when the sash is closed whereby when the top of said sash swings open on said links said pins will act as guides for the lower end of the sash, spaced stops on the rear 60 side of said guide channels adapted to engage said pins whereby said sash may rest thereon in selective positions, a latch attached to the header rail of said frame having spaced notches and a depending lever pivotally secured on the top rail 65 of said sash and having means adapted to operatively engage said notches whereby said sash may be manually pressed into its closed position or held in a slightly open position.

4. A device of the class described, comprising a

- frame and a sash therefor, each formed by similarly shaped and positioned Z bar irons whereby adjacent flanges contact when the sash is closed, the side members of said sash and frame being spaced to thereby form closures for the length of the sash when the sash is closed, guide members attached to the sides of said frame and adapted to cooperate with the outer flanges thereof and extending from the bottom to near the vertical center of the frame to thereby form guide channels, guide pins secured to the bottom of said sash which project into said guide channels, links positioned in said closures having their upper ends pivotally attached to said frame near the top thereof and having their lower ends pivotally attached to said sash at a point above the top of said guide channels when the sash is closed whereby when the top of said sash swings open on said links said pins will act as guides for the lower end of the sash, spaced stops on the rear side of said guide channels adapted to engage said pins whereby said sash may rest thereon in selective positions, means whereby when said sash is moved to its lowest position it is automatically moved outwardly at its bottom.
5. A device of the class described, comprising a frame and a sash therefor, each formed by similarly shaped and positioned Z bar irons whereby adjacent flanges contact when the sash is closed, the side members of said sash and frame being spaced to thereby form closures for the length of the sash when the sash is closed, instrumentalities in said closures whereby when said sash is raised 10 at its bottom on a line parallel to said frame, the top is moved relatively away from said frame, means in said channel adapted to engage the bottom of said sash whereby said sash may be selectively secured in various open positions, means 15 in the bottom of said channel whereby the lower end of said sash is automatically moved outwardly to its sealed position when closed, and manually operated means whereby the top of said sash may be moved into its sealed position. 20
